LOOSE LEAF BINDER

Filed May 15, 1930

UNITED STATES PATENT OFFICE

LOUIS STEIN, OF CHICAGO, ILLINOIS, ASSIGNOR TO L. M. STEIN COMPANY, OF CHICAGO, ILLINOIS, A CORPORATION OF ILLINOIS

LOOSE LEAF BINDER

Application filed May 15, 1930. Serial No. 452,553.

The invention relates generally to loose leaf binders of the type in which the leaves or sheets are secured by a plurality of spaced parallel posts between two pivoted wings on the covers of the binder, the posts being fixed on one wing and detachably secured to the other.

The wings of the binder are usually formed from metallic bars pivotally secured to cloth-bound covers of the binder by loops of the fabric binding extending from the cover around the metallic structure. In the past the posts have been secured on one of the metallic bars before being assembled in the binder, and have interfered with the operation of applying the fabric covering.

An important object of the present invention is to provide a loose leaf binder construction in which the posts may be attached to one of the wing bars after the fabric has been applied, whereby to facilitate the manufacture of the binder.

Another object of the invention is to provide in a loose leaf binder having a post adjacent to the top and bottom edges of the binder, individually operable locking devices whereby the free ends of the two posts may be detachably secured to one of the wings one at a time.

Another object of the present invention is to provide a binder of this character having a wing construction embodying means for securing the post to the wings and arranged to provide smooth outer surfaces on the wings so as to avoid any irregularity in the outer surface of the wings tending to cause wear on the covers.

Another object of the present invention is to provide a locking slide having new and improved gripping means for manually moving the slide, the gripping means having an operative position wherein it may be firmly grasped by an operator and being movable relatively to the slide to an out-of-the-way position in the space between the end edges of the leaves and the end edges of the covers whereby to permit the binder to be stood on its edge.

Other objects and advantages will become apparent from the following description

taken in connection with the accompanying drawings, in which:

Figure 1 is a fragmental perspective view of a loose leaf binder embodying the invention in its preferred form. 55

Fig. 2 is a fragmental perspective view showing the construction of the two wings of the binder, the various parts of the wing construction and one of the posts being separated from each other to illustrate the construction of the various parts. 60

Fig. 3 is an enlarged fragmental cross-sectional view taken through one of the posts. 65

Fig. 4 is a similar cross-sectional view taken through the two wings and showing the means which limits the longitudinal movement of the locking slides in one of the wings. 70

Fig. 5 is a cross-sectional view showing the frictional means for retaining the locking slides in their operative positions. 75

Fig. 6 is a longitudinal vertical cross-sectional view of one of the wing members.

While the invention is susceptible of various modifications and alternative constructions, I have shown in the drawings and will herein describe in detail the preferred embodiment, but it is to be understood that I do not thereby intend to limit the invention to the specific form disclosed, but intend to cover all modifications and alternative constructions falling within the spirit and scope of the invention as expressed in the appended claims. 80

In the preferred form illustrated, the invention is embodied in a binder having a pair of similar fabric-bound covers 10 flexibly connected together at corresponding edges by a flexible back 11. For the purpose of detachably securing suitably punched sheets of paper or the like in the binder, a pair of wings 12 and 13 are pivoted one to each of the covers 10 for swinging movement relatively to the covers, and a plurality of posts 14 extend between the two wings, each post having one end fixedly mounted in the wing 12 and detachably secured at its other end to the other wing 13. With such a construction, the wing 13 may be detached and moved away from the ends of the posts 14 and suit- 100

ably punched sheets of paper slipped over the projecting free ends of the posts, after which the paper may be held in place by securing wing 13 to the free ends of the posts.

5 As shown in Figs. 2, 3 and 4, the wing 12 is formed from an elongated metallic member designated generally by the numeral 15, the wing being pivotally secured to one of the covers 10 by means of a loop of fabric 16 10 which surrounds the member 15 and is fixed to the cover 10 by means of adhesive. In order to facilitate the manufacture of the binder, the member 15 is incorporated in the wing 12 before the posts 14 are mounted on 15 the member 15. This is accomplished, in the present instance, by forming the member 15 of sheet-metal bent to a substantially U-shaped cross-section to provide two spaced parallel plates 17 and 18 supported in fixed 20 relation to each other by the connecting portion 19 (Fig. 2) which constitutes the bight of the U. The member 15 thus formed is preferably positioned in the fabric loop 16 with the open end of the U adjacent the pivotal axis which is provided by the fabric and by this arrangement the rounded edge provided by the connecting portion 19 prevents undue wear of the fabric.

For the purpose of mounting the posts 14 30 on the member 15 a plurality of T-shaped openings 20 are formed in the member 15, the transverse portion of the opening being formed in the connecting portion 19 of the member 15 while the other portion of the 35 opening extends partially across the plate 17 transversely thereof. When the member has been mounted on the cover by means of the fabric 16, corresponding openings are formed through the fabric to permit the posts 40 14 to be inserted into the openings 20. Each post 14 has a flat head 21 (Figs. 2, 3 and 4) at one of its ends arranged so that it may be moved sidewise into the transverse section of the opening 20 and into a position in the 45 space between the two plates 17 and 18, in which position the post extends through the other portion of the opening 20 in perpendicular relation to the two plates.

As herein shown, the posts 14 are located 50 adjacent to the ends of the member 15 and to secure each of the posts in position on the member 15, a locking slide 22 is moved endwise into the space or longitudinal passage 55 between the two plates 17 and 18 to engage the head 21 of the post to prevent transverse or endwise displacement of the post. As shown in Figs. 2, 3 and 4, the head 21 of the post is of a thickness less than the space between the two plates 17 and 18 whereby to 60 permit transversely spaced fingers 23 (Fig. 2) formed on the locking slide to extend across the opening 20 between the head and the plate 17. Thus the fingers 23 may be made 65 of such a thickness that the flat lower surface

of the head 21 will be held against the plate 18 to provide a firm mounting for the post.

In the present instance, each post 14 is longitudinally extensible by means of a headed screw 24 (Fig. 3) which is threaded into 70 the post. When such extensible posts are employed it is desirable to prevent rotation of the posts and for this purpose the head 21 of each post has a pair of parallel flat surfaces 25 (Figs. 2 and 3) on opposite sides thereof. After the head 21 has been inserted into the opening 20, the post may be rotated to position the surfaces 25 parallel to the path of movement of the locking slide 22 and a pair of flanges 26 formed on the outer edges 75 of the fingers 23 engage the surfaces 25 to prevent rotation of the head 21 and the post 14.

Preferably the flanges 26 extend throughout the entire length of the locking slide 22 80 whereby to support the locking slide in spaced relation to the plate 18 and in abutting relation to the plate 17. This insures proper positioning of the locking slide so that when the head 21 is held in abutment with the plate 18, the fingers 23 will invariably move over the head 21 and into locking position. It also facilitates the fixing of the locking slide in the member 15 since the plate 17 may be struck downwardly after the parts have been 85 assembled to form a boss 17a which interlocks with the slide (Fig. 4). In the performance of such a fixing operation the plate 18 is not distorted and thus its smooth outer surface is retained and uneven wear of the cover 10 90 is prevented.

The wing 13 is constructed in a manner substantially similar to the wing 12 and has an elongated flat member 35 bent to a substantially U-shape to provide spaced parallel plates 36 and 37 which are maintained in fixed relation to each other by the connecting portion 38 of the U. The member 35 is pivoted to the other cover 10 by a fabric loop 39 for pivotal movement about the open side 100 of the U so that it may be moved into and out of abutting relation with the free headed ends 40 of the posts 14.

To receive the headed ends 40 of the posts, the plate 36 of the member 35 has a pair of transversely extending slots or openings 41 which in the present case extend to a point near the edge of the plate 36 which is fixed to the connecting portion 38. When the heads 40 of the posts have been moved through the slots 41 and into the space between the two plates 36 and 37 they may be detachably secured in this relation to the plates by locking means which is movable longitudinally in the space or passage between the two plates.

Preferably this means is arranged to permit either post to be locked to the wing 13 independently of the position of the other post with relation to the wing. This is accom-

plished by providing a separable locking slide 42 for each of the posts 14. As shown in Figs. 2 and 3, each locking slide 42 has a pair of spaced longitudinally extending fingers 42^a (Fig. 2) at one end arranged to engage the head 40 on its opposite sides and to extend across the slot 41 to hold the member securely on the post. Preferably each slide 42 has a longitudinally extending flange 43 at each edge arranged to engage the plate 37 to hold the body of the locking slide in engagement with the plate 36. To limit the longitudinal movement of the slide 42, a lug 44 (Figs. 4 and 5) is struck inwardly from the plate 36 and into a longitudinally extending slot 45 formed in the slide so that engagement of the lug 44 with the ends of the slot 45 determines the amount of endwise movement of the slide while engagement of the lug 44 with the sides 20 of the slot prevents the slide from rubbing against the fabric 39 which extends across the open end of the U. A boss 46 formed on the locking slide 42 engages an aperture 47 in the plate 36 when the locking slide has been moved to its operative position and serves to frictionally retain the locking slide in this position.

The operation of locking the wing 13 to the posts 14 may be simplified materially by making the openings 41 of the form shown in Fig. 2 wherein the opening is enlarged or of greater width along one side edge of the member 35 and tapers gradually toward the other edge of the member. Thus the headed end 40 of the posts may be projected readily through the enlarged portion of the opening 41 after which the member 35 may be moved transversely until the post abuts the narrow end of the opening 40. This action brings the member 35 and the post 14 into proper relation to permit the locking slide 42 at that end of the wing to be moved to its locking position.

The form of opening 41 herein shown is of particular advantage in securing the second post 14 to the wing 13, since it often happens that the free ends of the posts are tipped slightly toward or away from one another and the distance between the heads 50 thereof does not correspond with the distance between the centers of the openings 41. When this condition prevails, the wing 13 may be pivoted about the axis of the post with which it has been previously engaged, with the inner surface of the wing 13 in contact with the top of the other post 14 and when the enlarged end of the opening 41 is registered with the head 40, the wing will 60 move down over the post. The wing 13 may then be moved transversely until the post 14 abuts the small end of the opening 41 during which movement one of the sloping side edges of the opening 41 will cause relative movement of the post and the wing and will

position the post for operation of its locking slide 42.

The wing 13 usually extends within a short distance of the edges of the cover to which it is attached so that it will overlie the entire length of the sheets which are contained in the binder. Thus a comparatively short space is provided between the ends of the wing 13 and the bottom and top edges of the cover 10 and the locking slide 42 is preferably made of such a length that it projects substantially to the edge of the cover 10 when the locking slide is in its operative or locking position. This projecting portion of the locking slide is not sufficient to permit an operator to grasp the locking slide firmly and means is preferably provided on the projecting end of the slide to provide a firm grip for the same. In the present instance, this means comprises a pivoted member in the form of a ring 48 (Figs. 1, 2 and 6) secured to the locking slide 42 by a tongue 49 extending through the ring and reversely bent along the upper surface of the slide. The tongue 49 is formed by a longitudinal extension of the bottom wall of the channel-shaped locking slide 42.

The tongue 49 adjacent the bend is preferably enlarged to provide a pair of shoulders 50 lying in the path of the ring in its pivotal movement and arranged to limit the outward pivotal movement to provide an operative position for the ring 48. In the operative position determined by the shoulders 50, the ring 48 extends slightly beyond the edge of the cover 10 and is located at an angle of substantially 135° with respect to the body of the locking slide. Thus an operator may grasp the ring with his fore finger beneath the ring and his thumb on the outer surface of the ring for the purpose of withdrawing the locking slide to its inoperative position.

The portion of the ring 48 which projects beyond the edge of the cover 10 provides an outer surface 51 disposed at an angle to the edge of the cover 10 and when the cover is stood on its edge and slid onto a shelf, the angular surface 51 of the ring engages the shelf and cams the ring 48 about its pivotal axis and into an out-of-the-way position under the edge of the cover.

The shoulders 50 prevent the rings 48 from being pivoted outwardly into contact with the adjacent cover 10 and thus damage to the cover by the rings is avoided.

From the foregoing it will be apparent that the invention provides a loose leaf binder which may be manufactured economically since the metallic anchoring members of the wings may be mounted in the binder before the posts are attached thereto. It will also be apparent that the wings are constructed in a manner which avoids uneven wear on the outside of the covers of the binder.

It will also be seen that the invention provides a loose leaf binder which may be con-

veniently operated, since the posts may be secured individually to the wing 13 thus avoiding the necessity for properly positioning both of the posts prior to the operation of the locking means. The operation of the locking means is easily accomplished due to the provision of a convenient pivoted finger piece on the end of each locking slide and the fact that each finger piece has an angularly positioned surface thereon insures proper positioning of the finger piece when the binder is slid into position on a shelf.

I claim as my invention:

1. A loose leaf binder comprising a pair of covers, a back flexibly connecting said covers, a pair of wings one pivotally connected to each of said covers, each wing comprising an elongated substantially flat member having a longitudinally extending passage therein opening through the end of said member and also having an aperture in one side thereof opening into said passage, a post having an enlarged head insertable into the passage in one of said members through the side opening in said member, a locking slide insertable into said last-mentioned passage from the end of said member and engageable with said head to prevent withdrawal of said post from said member, the other end of said post being adapted to be inserted into the passage in the other member through the aperture therein, and a locking slide in the passage of said other member operable to detachably secure said post to said other member.
2. A loose leaf binder comprising a pair of covers, a back flexibly connecting the covers, a pair of wings one pivotally connected to each of said covers, each of said wings comprising a pair of flat plates fixed in parallel spaced relation to each other, and one of the plates of each wing having an opening therein, a post adapted to have its opposite ends positioned in the openings in the two wings, a locking member inserted into the space between the two plates of one wing to fix said post thereto, means acting between said member and the apertured one of said last-mentioned plates to hold said member in its operative position, and a locking slide movable longitudinally in the space between the plates of the other wing and engageable with said post to detachably secure the other end of said post to said other wing.
3. In a wing construction for loose leaf binders, the combination of a pair of elongated flat plates secured in parallel spaced relation to each other, one of said plates having a slot formed therein extending transversely from one edge thereof toward the other edge but terminating short of said other edge, a post of a diameter substantially equal to the width of said slot, a head on said post of a greater width than said slot and arranged to be moved between said plates when said post is moved sidewise into said slot and

to engage the inner surface of one of said plates to prevent longitudinal movement of the post, a locking member insertable into the space between said plates, a longitudinally projecting part on one end of said locking member arranged to engage a side edge of said head to prevent sidewise withdrawal of said post from said slot.

4. A loose leaf binder having a wing construction comprising a substantially flat member having a longitudinally extending passage therein opening through one end of said member and also having an aperture in one side thereof opening into said passage, a post having an enlarged head insertable into said passage through said aperture, and a locking slide insertable into said passage through the end of said member and engageable with said post to retain said post in position on said member and prevent rotation of said post relatively to said member.

5. In a wing construction for loose leaf binders, the combination of an elongated substantially flat member having a longitudinally extending passage therein opening through one end of said member, said member also having an aperture in one side thereof, a post having a head insertable into said passage through said aperture, a locking slide adapted to be inserted into the end of said passage and having fingers thereon arranged to extend past the sides of said post to maintain said post in position on said member, the head of said post having a flattened side edge, and a flange extending longitudinally along one edge of said slide arranged to engage the flattened side of said head to prevent rotation of said post.

6. A wing construction for loose leaf binders comprising a pair of elongated flat plates fixed in spaced parallel relation to each other, a first one of said plates having an opening therein, a post having a headed end adapted to project through said opening in said first plate and into contact with the other of said plates, a locking slide movably mounted between said plates, means to maintain said slide adjacent to said first plate and in spaced relation to said other plate, said head being of a thickness less than the space between said slide and said other plate, and means on said slide arranged to engage said head to hold said post against endwise withdrawal from said opening.

7. A wing construction for loose leaf binders comprising a pair of elongated flat plates fixed in spaced parallel relation to each other, a first one of said plates having an opening therein, a post having a headed end adapted to project through said opening in said first plate and into contact with the other of said plates so that said post is disposed perpendicularly with respect to said plates, a locking slide movably mounted between said plates, means to maintain said

- slide adjacent to said first plate and in spaced relation to said other plate, said head being of a thickness less than the space between said slide and said other plate, said slide having means thereon arranged to engage said head to hold said post against endwise withdrawal from said opening, said slide also having a longitudinally extending slot formed therein, and a lug struck inwardly from said first plate and engaging the slot in said slide to limit the longitudinal movement of said slide.
8. A wing construction for loose leaf binders comprising a pair of elongated flat plates fixed in spaced parallel relation to each other, a first one of said plates having an opening therein, a post having a headed end adapted to project through said opening in said first plate and into contact with the other of said plates so that said post is disposed perpendicularly with respect to said plates, a locking member mounted between said plates, said member having a flat section with similarly disposed longitudinally extending flanges along its sides, said flanges being adapted to engage said other plate to maintain said flat section of said member adjacent to said first plate, the head on said post being of a thickness slightly less than the space between said flat section and said other plate, a finger formed at one end of said flat section arranged to engage said head and the side of said post to hold said post in position relatively to said plates, and means acting between said first plate and said locking member to limit movement of said locking member with relation to said plates.
9. A wing construction for loose leaf binders comprising, in combination, an elongated strip of sheet-metal bent to form an elongated member of substantially U-shaped cross-section and having a longitudinally extending space between the two sides of said member, said member having a slot formed therein opening laterally through the bottom section of said U, a post having an enlarged head adapted to be inserted into said slot by transverse movement of said head through said slot, said head being of a less thickness than said space, and a locking member adapted to be inserted into said space from the end of said member, said locking member also being of less thickness than said space, and the combined thickness of said locking member and said head being substantially equal to the thickness of said space, said locking slide having a finger projecting from one end thereof adapted to engage one side of said post to prevent withdrawal of said post from said slot.
10. A wing construction for loose leaf binders comprising, in combination, an elongated strip of sheet-metal bent to form an elongated member of substantially U-shaped cross-section with a longitudinally extending space between the two spaced

- sides of the U, said member having a T-shaped opening formed therein consisting of a first portion in the connecting section of the U and a second portion extending from said first portion partially across one side of said U, a post having a head adapted to be inserted sidewise into said second portion of said opening to position said head in the space between said sides of the member, and a locking slide insertable into the end of said space and having a part thereon adapted to extend across said second portion of said opening to engage said head and prevent sidewise withdrawal of the head from said opening.
11. In a loose leaf binder having a cover, the combination of a wing construction comprising a sheet of metal bent to form an elongated member of substantially U-shaped cross-section having smooth parallel outer surfaces, a loop of fabric extending around said member and secured to the inner side of said cover to pivot said member to said cover for pivotal movement about the open edge of said U, said member and said fabric having registering openings therein providing a substantially T-shaped slot, the transverse portion of said slot being positioned along the closed edge of said U and the other portion of said slot extending transversely across a portion of the inner side of said member, a post having an enlarged head insertable into said slot to position said post in perpendicular relation to said member and projecting from the inner side of said member through said other portion of the slot, a locking slide insertable into the space between the two sides of said U, said slide having longitudinally extending flanges along its edges arranged to engage the inner surface of the outer side of said U and to maintain said slide in engagement with the inner side of said U, said slide having fingers at one of its ends arranged to extend on opposite sides of said post and to engage said head to maintain said post in position on said member, the inner side of said U being upset into engagement with said locking slide to maintain said slide in its operative position.
12. A locking slide for a loose leaf binder, said slide comprising an elongated flat section with similarly disposed flanges extending longitudinally along the sides of said flat section, and a pair of transversely spaced fingers projecting from one end of said slide in the plane of said flat section.
13. A loose leaf binder comprising, in combination, a pair of covers pivotally connected together, a pair of wings pivotally mounted one along an edge of each of said covers, a pair of posts each having one end fixed on one of said wings so that said posts project perpendicularly from said wing, the other one of said wings having a pair of openings in one side thereof adapted to receive the other

ends of said posts, said openings being enlarged adjacent to one edge of said wing and terminating in a narrow portion short of the other edge of said wing, and a pair of locking devices movable longitudinally of said other wing and operable to lock said posts one at a time to said other wing.

14. A loose leaf binder comprising, in combination, a pair of covers, a pair of wings, one pivotally mounted on each of said covers, a pair of posts each having one end fixed on one of said wings, means slidable longitudinally on the other of said wings operable to releasably secure the other ends of said posts to said other wing, and gripping means pivotally mounted on said slidable locking means for the manual operation thereof.

15. A loose leaf binder comprising, in combination, a pair of covers, a pair of wings, one pivotally mounted on each of said covers, a post having one end fixed on one of said wings, a locking slide mounted on the other of said wings and slidable longitudinally thereof to releasably secure the other end of said post to said other wing, one end of said slide being positioned adjacent to one edge of said cover, and means for manually gripping said locking slide comprising a finger piece pivoted on said slide, said finger piece being movable to an inoperative out-of-the-way position substantially at right-angles to said slide and also being movable to an operative position substantially 45° removed from said out-of-the-way position, and stop means arranged to determine the operative position of said finger piece.

16. In a loose leaf binder having flexibly connected covers, a pair of wings pivotally connected one to each cover along corresponding edges thereof, a post having one end fixed in one of said wings, and a locking slide movable longitudinally of the other wing and operable to detachably secure the other end of said post to said other wing, in combination with a finger piece mounted pivotally on one end of said slide and movable about its pivot to a position wherein it projects beyond one edge of said cover, said pivotal axis being substantially parallel to said last-mentioned edge of the cover when said cover is in closed position, said finger piece having a surface formed thereon at an angle to said axis and arranged to act as a cam to move said piece about its pivot when said binder is stood on its end and slid onto a shelf.

17. In a loose leaf binder having a back, a pair of covers pivoted to said back, a pair of wings one pivotally connected to each cover, a post having one end fixed to one of said wings, a locking slide movable longitudinally on said other wing and operable to detachably secure the other end of said post to said other wing, said slide projecting at one end from said wing, a finger piece pivotally connected to said projecting end of the slide for swing-

ing movement about an axis perpendicular to the path of movement of said slide, and stop means on said slide engageable with said finger piece to maintain said piece out of contact with the adjacent cover.

18. A loose leaf binder comprising, in combination, a pair of covers, a pair of wings, one pivotally mounted on each of said covers, a post having one end fixed on one of said wings, a locking slide movable longitudinally on the other of said wings operable to releasably secure the other end of said post to said other wing, and gripping means comprising a ring pivotally mounted on the end of said locking slide.

In testimony whereof, I have hereunto affixed my signature.
